APPARATUS FOR SMELTING

Glenn H. McIntyre, Cleveland Heights, and Robert W. Stuart, Garfield Heights, Ohio, assignors to Ferro Enamel Corporation, Cleveland, Ohio, a corporation of Ohio

Application May 11, 1937, Serial No. 141,963

8 Claims. (Cl. 49—54)

This invention relates as indicated to a method of and apparatus for smelting and more particularly to the production of materials such as glass and more particularly porcelain enamel.

3 It is a principal object of our invention to provide a method of and apparatus for smelting characterized by the fact that the smelting operation is carried on continuously and by means economical in operation and insuring a superior finished 10 product.

Other objects of our invention will appear as the description proceeds.

To the accomplishment of the foregoing and related ends, said invention, then, consists of the 15 means hereinafter fully described and particularly pointed out in the claims; the annexed drawing and the following description setting forth in detail certain means and one mode illustrating, however, but one of the various ways in 20 which the principle of the invention may be used.

In said annexed drawing:—

Fig. 1 is a horizontal section through an apparatus constructed in accordance with the principles of our invention and Fig. 2 is a transverse sectional view of the apparatus illustrated in Fig. 1, taken on a plane substantially indicated by the line 2—2.

Referring now more specifically to the drawing and more especially to Fig. 1, the smelter generally indicated at 1, is substantially rectangular in form, divided by an inner partition 2 separating the same into a melting chamber 3 and a fining chamber 4.

The chamber 3 is hereinafter referred to as a melting chamber since therein the raw materials are substantially all reduced to a molten state. The chamber 4 is referred to as a fining chamber for the reason that therein the previously melted raw material is maintained in an elevated temperature for a sufficient length of time to refine the same, i. e., remove "seeds" and the like therefrom which is necessary prior to the discharge of the material.

Connecting the chambers 3 and 4 at one end 15 thereof is a melted material passage 5 extending through the lower portion of the wall 2. Connecting the chambers 3 and 4 at their ends opposite to the melted material passage 5 is a gas passage 6 extending through the wall 2 in the upper portion thereof. Associated with one end of the melting chamber 3 is a conventional "dog house" 7 employed for the purpose of feeding the raw materials to the melting chamber at one end thereof. The construction and operation of the 15 feeding means commonly employed for this pur-

pose is believed to be sufficiently well known to those familiar with the art so that a further description and illustration thereof is unnecessary.

At the charging end of the melting chamber 3 is an auxiliary combustion chamber 8, the bottom 5 or hearth 9 of which is preferably at an elevation above the bath level in the chamber 3. A burner 10 for projecting a suitable hydrocarbon fuel such as gas or oil into the melting chamber projects into the back-end of the auxiliary combustion 10 chamber 8. The employment of the auxiliary combustion chamber 8 is particularly desirable when a liquid fuel is burned so as to insure complete volatilization of all of the liquid fuel before the flame projects over the bath, otherwise drippings of the liquid fuel might fall into the bath and contaminate the same. When the auxiliary combustion chamber is employed, the drippings from the burner 10 fall onto the heated hearth 9 where they are volatilized before being projected 15 into the burning zone over the bath in the chamber 3.

The hearth or bottom of the melting chamber 3 slopes substantially uniformly in the direction indicated by the line 11 from the charging opening 25 or "dog house" to the melted material passage 5. The hearth of the fining chamber 4 similarly slopes upwardly from the melted material passage 5 to the continuous discharge opening 12. The elevation of the discharge opening 12 is between the upper edge of the melted material passage 5 and the lower edge of the gas passage 6 so that the level of the bath maintained in the smelter is at all times a substantial distance above the opening 5. The hearth of the fining chamber 35 4 slopes to a low point at 13 which is directly opposite a draining opening 14, the draining opening 14 will be normally closed, however. If, for any reason, it should be desired to drain the smelter of all glass, the feed of the raw material 40 is stopped and the draining opening 14 opened and the smelter permitted to drain until empty.

Positioned in one corner of the fining chamber 4 is a stack or main flue 15 which communicates with the fining chamber through branched openings 16 and 17. By dividing the flow of heated gases by means of the branched passages 16 and 17, a stream of such heated gases is directed through the restricted area opposite the melted material passage 5. Another stream of heated 50 gases drawn by the branched opening 16 is caused to sweep over the central area of the fining bath, maintaining the same at the desired temperature.

An auxiliary burner 18 in the end of the fining 55

chamber adjacent the gas passage 6 and the continuous discharge opening 12 may be employed for the purpose of augmenting the heating effect of the gases flowing into the fining chamber from the melting chamber and to also assist in equalizing the temperatures within the various areas of the fining chamber.

An important characteristic of the smelter above described is the manner in which the work material and the heating gases are carried therethrough. It will be observed that the work material flows in loop fashion through the smelter. This provides a maximum distance of flow for the material in the compact rectangular furnace structure and makes possible the conservation of the heat of the burning gases employed for the purpose of melting and fining the material.

Of greater importance, however, is the manner in which the heating flame or heated gases are projected through the smelter. It will be observed that the heating flame passes in a loop through the melting chamber. This loop of flame in the melting chamber, not only renders more uniform the heating effect of such flame but also is effective to maintain the various areas of the melting chambers at the desired temperature. The manner in which the flame loops through the melting chamber is particularly effective to, first, immediately reduce the raw materials entering the melting chamber from the "dog house" to a molten condition, and second, to maintain the temperature of the bath adjacent the melted material passage 5 sufficiently high so as to prevent freezing or congealing at this point.

The direction of flow of the primary stream of gas in the fining chamber is in accordance with desirable practice counter to the flow of the melted material and the division of this primary stream of heated gases into two separate streams before passing out of the stack in the manner and for the purposes previously described is likewise highly advantageous.

By employing a smelter of the construction described it is possible to, in a smelter of very compact construction, melt and fine a relatively large amount of material in a short time, this being due to the very efficient manner in which the burning gases are led through the smelter and the relation of such flow to the direction and manner of flow of the melted material.

Other modes of applying the principle of our invention may be employed instead of the one explained, change being made as regards the means and the steps herein disclosed, provided those stated by any of the following claims or their equivalent be employed.

We, therefore, particularly point out and distinctly claim as our invention:—

1. A melting furnace comprising laterally contiguous melting and fining chambers respectively provided with a charging opening for the raw material and a discharge opening for the melted material, a passage for melted material from one end of said melting chamber to the adjacent end of the fining chamber, a passage for gases from said melting chamber to the fining chamber at a point spaced longitudinally of said melting chamber from said melted material passage, a burner in said melting chamber at the end opposite said melted material passage, and a flue opening in said fining chamber.

2. A melting furnace comprising laterally contiguous melting and fining chambers respectively provided with a charging opening for the raw material and a discharge opening for the melted

material, a passage for melted material from one end of said melting chamber to the adjacent end of the fining chamber, a passage for gases from said melting chamber to the fining chamber at a point spaced longitudinally of said melting chamber from said melted material passage, a burner in said melting chamber at the end opposite said melted material passage, and a flue opening in said fining chamber in the end adjacent said melted material passage.

3. A melting furnace comprising laterally contiguous melting and fining chambers respectively provided with a charging opening for the raw material and a discharge opening for the melted material, a passage for melted material from one end of said melting chamber to the adjacent end of the fining chamber, a passage for gases from said melting chamber to the fining chamber at a point spaced longitudinally of said melting chamber from said melted material passage, a burner in said melting chamber at the end opposite said melted material passage, and a flue opening in said fining chamber in an area intermediate of said melted material passage and said discharge opening.

4. A melting furnace comprising laterally contiguous melting and fining chambers respectively provided with a charging opening for the raw material and a discharge opening for the melted material, a passage for melted material from one end of said melting chamber to the adjacent end of the fining chamber, a passage for gases from said melting chamber to the fining chamber at a point spaced longitudinally of said melting chamber from said melted material passage, a burner in said melting chamber at the end opposite said melted material passage, and a flue opening in said fining chamber having branches respectively leading from areas adjacent said melted material passage and said discharge opening.

5. A melting furnace comprising laterally contiguous melting and fining chambers respectively provided with a charging opening for the raw material and a discharge opening for the melted material, separate passages respectively for burning gases and melted material connecting opposite ends of said chambers, a burner arranged in one wall of said melting chamber adjacent said passage for burning gases for projecting a heating flame in a loop through said melting chamber and through said burning gas passage into said fining chamber and a flue opening in said fining chamber.

6. A melting furnace comprising laterally contiguous melting and fining chambers respectively provided with a charging opening for the raw material and a discharge opening for the melted material, separate passages respectively for burning gases and melted material connecting opposite ends of said chambers; a burner arranged in one wall of said melting chamber adjacent said gas passage for projecting a flame in a loop through said melting chamber and into said fining chamber and a flue opening in said fining chamber, said charging and discharge openings and said passage for melted material being so arranged that the work material flows in looped fashion through said furnace.

7. A melting furnace comprising laterally contiguous melting and fining chambers respectively provided with a charging opening for the raw material and a discharge opening for the melted material, separate passages respectively for burning gases and melted material connecting opposite ends of said chambers, a burner arranged in

- One wall of said melting chamber adjacent said gas passage for projecting a flame in a loop through said melting chamber and into said fining chamber and a flue opening in said fining chamber in the same end with said melted material passage, said charging and discharge openings and said passage for melted material being so arranged that the work material flows in looped fashion through said furnace.
- 5 8. A melting furnace comprising laterally contiguous melting and fining chambers separated by a common wall and respectively provided with a charging opening for the raw material and a dis-

charge opening for the melted material, separate passages through said common wall at opposite ends thereof for the flow of burning gases and melted material from said melting chamber to said fining chamber, a burner arranged in the 5 wall of said melting chamber adjacent said gas passage for projecting a heating flame in looped fashion through said melting chamber and into said fining chamber and a flue opening in said fining chamber.
